Primary Examiner — Rosemary K Tarcza*Assistant Examiner* — Alison M Ofstun(74) *Attorney, Agent, or Firm* — Stine Law Ltd(57) **CLAIM**

The ornamental design for a battery housing, as shown and described.

DESCRIPTION

FIG. 1 is a front perspective view of a battery housing showing our new design;

FIG. 2 is a front bottom perspective view thereof;

FIG. 3 is a front elevational view thereof;

FIG. 4 is a right side elevational view thereof;

FIG. 5 is a rear elevational view thereof;

FIG. 7 is a top plan view thereof; and,

FIG. 8 is a bottom plan view thereof.

The broken lines present in the figures are included for the purpose of illustrating portions of the article which form no part of the claimed design.

1 Claim, 7 Drawing Sheets(56)
